UNITED STATES PATENT OFFICE.

HENRY D. ZEHRBACH, OF BLUFFTON, OHIO, ASSIGNOR OF ONE-HALF TO ADAM D. LUGIBIHL,
OF BLUFFTON, OHIO.

CASTING.

No. 908,828.

Specification of Letters Patent.

Patented Jan. 5, 1909.

Application filed October 15, 1908. Serial No. 457,890.

To all whom it may concern:

Be it known that I, HENRY D. ZEHRBACH, a citizen of the United States, residing at Bluffton, in the county of Allen and State of Ohio, have invented a new and useful Casting, of which the following is a specification.

This invention relates to sight glasses for cream separators and has for its object to provide a comparatively simple and inexpensive device of this character especially designed for attachment to gravity cream separators to permit inspection of the contents of the milk containing vessel during the separating process.

15 A further object of the invention is to provide a frame or casting having a seat on one side thereof for the reception of a sight glass and provided at its lower end with an opening the interior walls of which are threaded 20 for engagement with a faucet.

A further object is to provide a link for retaining the sight glass to its seat in the casting, and means for locking the link against accidental displacement.

25 Further objects and advantages will appear in the following description, it being understood that various changes in form, proportions and minor details of construction may be resorted to within the scope of 30 the appended claims.

In the accompanying drawings forming a part of this specification:—Figure 1 is a longitudinal sectional view of a combined sight glass and faucet seat constructed in accordance with my invention, showing the same 35 in position on a cream separator. Fig. 2 is a front elevation of the same with the faucet removed. Fig. 3 is a detail perspective view of the supporting frame or casting detached, 40 the sight glass and retaining link being shown detached from the casting.

Similar numerals of reference indicate corresponding parts in all of the figures of the drawings.

45 The sight glass forming the subject matter of the present invention is principally designed for attachment to that class of cream separators in which a single vessel is employed for containing the milk and water, 50 and in Fig. 1 of the drawings is shown in connection with such a separator, in which 5 designates the liquid containing vessel having an inclined bottom 6 and provided with a depending supporting flange 7.

The device consists of a supporting frame 55 or casting 8 having a marginal flange 9 adapted to bear against the exterior wall of the receptacle 5 and provided with a lateral extension 10 which projects within the receptacle 5, as shown, the metal around the 60 opening in the receptacle 5 being bent laterally and soldered or otherwise rigidly secured to the extension 10, as indicated at 11.

Projecting inwardly from the casting 8 at 65 the extension 10 is a flange 12 which forms a seat for a sight glass 13, the latter being retained in position on the flange 12 by a hollow frame or link 14.

Formed in the end walls of the extension 70 10 are recesses 15 in which are soldered or otherwise secured suitable locking lugs 16, the terminals of which are adapted to be bent downwardly in contact with the link 14, thereby to retain said link in engagement 75 with the glass 13 and prevent accidental displacement of the latter during transportation or shipment of the separator.

The lower end of the casting 8 is curved or rounded at 17 and provided with a centrally 80 disposed opening 18, the interior walls of which are threaded for engagement with the correspondingly threaded terminal of a faucet 19.

The bottom of the receptacle 5 at the 85 threaded end of the faucet is deflected downwardly at 20 so as to permit the cream in the receptacle 5 to be readily drawn off through the faucet when the latter is moved to open position.

90 The face of the casting 8 at the curved portion thereof is cut away to produce horizontally aligned recesses 21 adapted to receive the reinforcing bead 22 of the bottom 6, thereby to assist in retaining the casting in 95 proper position on the containing vessel.

In assembling the several parts an opening is first formed in the receptacle 5, after which the casting 8 is introduced within the opening with the flange 9 bearing against the exterior walls of the receptacle and with the extension 10 projecting within the said receptacle, as best shown in Fig. 1 of the drawings. The glass is then positioned on the flange 12 and the link 14 moved laterally in engagement with the rear face of the glass, after which a small quantity of putty, cement or other adhesive material is introduced within 100 105

the seating recess and the lugs 16 pressed laterally against the rear face of the link, thereby to retain the link and sight glass in position on the casting. After the parts are 5 thus assembled, the faucet 19 is screwed into the opening 18 in the usual manner.

It will thus be seen that there is provided a combined sight glass seat and faucet seat, capable of being readily attached to a separator 10 employing a single liquid containing vessel and in which liability of breakage of the sight glass is reduced to a minimum, and a firm anchorage formed for the faucet, thus obviating the necessity of soldering the faucet on the containing vessel and the employment 15 of metal gages heretofore used on this class of cream separators.

Having thus described the invention what is claimed is:

- 20 1. The combination with a single wall liquid containing vessel, of a sight glass frame permanently secured to and projecting within the vessel and provided with an opening, a faucet seated in said opening, a sight glass carried by the frame, and means for locking the glass against accidental displacement.
- 25 2. The combination with a single wall liquid containing vessel, of a sight glass frame having a marginal flange arranged to bear against the exterior walls of the vessel and provided with an extension projecting within and permanently secured to the receptacle, said frame being provided with an elongated seat and having a threaded opening formed in one end thereof, a faucet threaded in said opening, a sight glass engaging the seat, and means for locking the sight glass against accidental displacement.
- 30 3. The combination with a single wall liquid containing vessel, of a sight glass frame having a flange adapted to bear against the exterior wall of the vessel and provided with an extension projecting within said vessel and provided with an opening, a faucet seated in said opening, a sight glass carried by the frame, a link bearing against the glass, and lugs engaging the link for locking the latter in engagement with the glass.
- 35 4. The combination with a single wall liquid containing vessel, of a sight glass frame permanently secured to and projecting within the vessel and provided with an opening, a faucet seated in said opening, a sight glass carried by the frame, a link bearing against the sight glass, and lugs secured to the frame and adapted to be bent laterally in contact

with the rear face of the link for locking the latter in engagement with the sight glass.

5. The combination with a liquid containing vessel having an opening formed therein, a sight glass frame seated within said opening and having its front portion provided with a laterally extending flange arranged to bear against the exterior wall of the vessel and its rear portion formed with an extension projecting within the receptacle, the material forming the vessel being bent laterally and secured to the extension of the frame at said opening, a sight glass carried by the frame, a faucet piercing the lower end of the frame and communicating with the interior of the vessel, and means for locking the sight glass against accidental displacement.

6. The combination with a liquid containing vessel having a reinforcing rib, of a sight glass frame having a marginal flange arranged to bear against the exterior wall of the vessel and provided with a lateral extension projecting within the vessel, the lower end of the frame being provided with a threaded opening and having horizontally alined recesses formed therein at said opening and adapted to receive the reinforcing rib of the receptacle, a faucet threaded in said opening, a sight glass carried by the frame, a link bearing against the sight glass, and lugs carried by the frame and adapted to be bent into engagement with the link.

7. The combination with a liquid containing vessel, of a sight glass frame having a marginal flange arranged to bear against the exterior wall of the receptacle and provided with an inwardly extending flange constituting a seat, there being a threaded opening formed in one end of the frame, a sight glass resting on the inwardly extended flange, a link bearing against the sight glass, there being recesses formed in the opposite ends of the frame at the inwardly extending flange, lugs seated in said recesses and adapted to be bent in contact with the link, and a faucet having one end thereof threaded for engagement with the threaded walls of the opening and communicating with the interior of the vessel.

In testimony that I claim the foregoing as my own, I have hereto affixed my signature in the presence of two witnesses.

HENRY D. ZEHRBACH.
